UNITED STATES PATENT OFFICE.

JAMES A. CAMERON, OF CHICAGO, ILLINOIS, ASSIGNOR TO EASTMAN KODAK COMPANY,
OF ROCHESTER, NEW YORK, A CORPORATION OF NEW YORK.

FOLDABLE EASEL MOUNT.

Application filed December 19, 1924. Serial No. 757,051.

This invention relates to foldable easel mounts. One object of the invention is to provide an improved easel mount in which the parts are relatively simple and inexpensive and yet are positively retained in their relative positions. Other objects will hereinafter appear.

In the accompanying drawing in which like reference characters denote like parts throughout,—

Fig. 1 is a perspective view showing the parts of the easel mount in the easel position;

Fig. 2 is a rear elevation with the parts of the device in the easel position;

Fig. 3 is a sectional view taken on the line 3—3 of Fig. 1;

Fig. 4 is a top plan view with the parts of the device in easel position;

Fig. 5 is a rear elevation with parts of the device folded for the sake of clearness.

This invention is a simplification and improvement of the easel shown in my prior Patent No. 1,396,724, granted November 15, 1921. I have found that the sliding tongue, which acts as a brace for the flaps, in the construction shown in said patent, may be greatly simplified. I have also found that it may be modified so as to forcibly hold the parts in position. This, moreover, may be accomplished without thickening the easel when the parts are folded up. In fact the thickness may be decreased in the preferred form of my invention.

Referring to the accompanying drawing, 1 represents a picture-receiving panel comprising a front wall 2, say of stiff cardboard, for example, and a rear wall 3, preferably of springy sheet material, such as a good grade of cardboard. These two walls are joined together by any suitable adhesive.

At the side edges of the picture-receiving panel 1 are provided wings 4—4. I find it convenient to form these wings integral with the rear wall 3 of the panel. They fold against the rear face of the panel,—that is, against the rear face of the rear wall 3, moving in the direction of the arrows in Fig. 4. Moreover, in the preferred form of my invention the folds 5—5 about which the side wings 4 turn are pressed down sufficiently firmly so that the side wings 4 tend to lie nearer the rear wall 3 than the position indicated in Fig. 4. In

other words the spring in the cardboard material at the folds 5 normally tends to force wings 4 in the direction of the arrows in Fig. 4.

On the rear face of the panel 1 I provide a retaining tongue 6 provided with shoulders 7 which extend slightly toward the panel when the tongue is in the position shown in Figs. 1, 2, 3 and 4. While this tongue may be attached to the rear wall 3 in any suitable manner, I prefer to form it as an integral part of said wall, said tongue being cut out of the springy sheet material of rear wall 3, so as to leave an upper horizontal fold 8 about which it swings. The tongue, therefore, can swing down into the recess 9,—in other words into the hole in the rear wall 3, which was made by cutting out said tongue 6. This enables the tongue to fold back into the plane of the rear wall 3 and thus provide a minimum thickness.

By reason of the springy nature of the material in the tongue 6 and by reason of making only a minimum bend at 8, said tongue 6 tends to spring or swing downwardly about the fold 8 toward recess 9. In this way it tends to occupy a position below that shown in Fig. 3. Consequently as long as the shoulders 7 engage the edges of the said wings 4, so that tongue 6 cannot swing downwardly, said shoulders 7 are kept forcibly in locking engagement with said edges of side wings 4. The springiness of the fold 8 causes a positive force to be applied by the tongue 6 against the wings 4 so as to retain them in easel position. This is a very great convenience and prevents annoying disengagement of the parts when the easel mount is in use.

In the preferred form of my invention with the wings 4 and tongue 6 tending to fold toward the rear face of the panel 1, the parts can be quickly brought to easel position by merely swinging up the tongue 6 and then letting go of it. Slanting edges 10 of the tongue cam the wings 4 outwardly as the tongue moves upwardly. Then when the tongue is released it springs down and catches the shoulders 7 against the outer edges of the side wings.

The picture 11, usually a photograph, may be attached to the front face of the panel in any suitable or preferred manner, such as by an adhesive or the like. In the present

instance I have illustrated the picture 11 as detachably held in position by the corner pockets 12.

Having thus described my invention, what I claim as new and desire to secure by Letters Patent is:

A foldable easel mount for pictures comprising a picture-receiving panel having a front wall and a rear wall, said panel being provided with two side wings adapted to be swung into folded position against the rear face of the panel and to be swung into easel supporting position at an acute angle to the rear face of said panel, the material at the joints between the panel and wings being flexed to normally spring the wings toward and adjacent said rear face of the panel and toward and adjacent the hereinafter mentioned shouldered tongue, said rear wall being provided with a shouldered tongue of springy material adapted to swing against the rear face of the panel into folded posi-

tion, and to swing about a fixed upper horizontal fold to bring its shoulders into engagement with the free edges of said wings and retain them in easel-supporting position, the spring of the material at said fold tending to move said tongue downward toward its said folded position and forcibly retain said shoulders against said edges of the wings; said tongues and said wings having smooth inclined cam edges, whereby said easel mount may be changed from folded to easel position by merely swinging up said tongue beyond its easel position and releasing it, said smooth inclined cam edges sliding over each other to cam the wings apart until the parts reach easel position, said tongues having shoulders to limit said sliding when the easel position is reached. 40

Signed at Chicago, Illinois, this 11th day of December, 1924.

JAMES A. CAMERON.
